UNITED STATES PATENT OFFICE.

HARRY WALTER STERTZBACH, OF COLUMBUS, OHIO, ASSIGNOR TO THE BUCKEYE STEEL CASTINGS COMPANY, OF COLUMBUS, OHIO.

CAST SIDE FRAME FOR CAR TRUCKS.

Application filed March 18, 1925. Serial No. 16,445.

This invention relates to cast side frames for car trucks and has special reference to an improvement in construction which will facilitate manufacture without increasing cost, 5 expedite the removal of the core from the mold, and lessen or eliminate imperfections caused by shrinkage. The invention will be first fully described and then particularly defined in the appended claims.

10 In the accompanying drawing, Figure 1 is a side elevation of a portion of a side frame of the type shown in Letters-Patent No. 1,523,793, issued January 20th, 1925, upon an application filed by M. R. Hansen and 15 myself.

Figure 2 is a view showing the side frame in section on the line 2—2 of Figure 1, hatching being employed to represent portions of the mold and the cores.

20 In the type of side frame illustrated and above mentioned, the tension member 1 and compression member 2 merge into the top of the journal box 3 and the tension member runs continuously from the top of the spring 25 seat directly to the top of the journal box, the tension and compression members being of inverted channel form in cross section.

It is the usual practice in the manufacture 30 of car truck side frames to make molds and cast the frames on their sides, the inside or hollowed out portion of the channels being formed by cores 5 and 6 which are placed in the mold, indicated at 7, the parting of the mold being midway between the sides as indicated by the line 8. In the usual construction, the width of the compression member is 35 that indicated by the line 9—10 and the width of the tension member is the same as that of the compression member, but by the 40 present invention the width of the tension member is greater than the compression member and is represented by the line 11—12.

In steel castings of this type, it is desirable 45 to have large radii at the corners, 13, 14, for the reason that the more gradually the change in direction between the plate and flanges is effected the more completely will shrinkage imperfections in the corners be 50 eliminated. The radius of the corners 13 is not limited by the method of manufacture 55 because, whether it be large or small, the pattern can be readily drawn from the mold. In the usual construction at the corners 14, however, the radius is limited because it is not convenient to make it greater than the

thickness, 15, of the side flanges of the compression member. If it be made greater, at the same time maintaining the width 9—10, the straight edge 16 of the core 6 would have to be curved at its ends to conform to the curvature of the corners 14, thus interfering seriously with the simplicity of the core and increasing the cost. In the improved construction, the straight edge of the core is maintained and the corner 14 may have a 60 large radius by increasing the width of the tension member, as shown, so as to permit the formation of the corner entirely outside the core. This construction will permit the use of a radius as large as desired without 65 resorting to additional cores or adding to the expense of manufacture of cores now in use. For manufacturing reasons, the increase in width will occur more or less abruptly along the lines 17—18 and 19—20, Figure 1, 70 the outstanding flanges along these lines concealing any abrupt offset which might be 75 unsightly except for these flanges.

Having fully described my invention what I claim as new and desire to secure by Letters Patent, is:—

1. A cast side frame for car trucks having tension and compression members of inverted channel formation, the width of the tension member being greater than the width of the compression member whereby the corners of the tension member may be formed upon a large radius.

2. A cast side frame for car trucks having tension and compression members of inverted channel formation, the width of the tension member being greater than the width of the compression member and being abruptly increased through portions near both its ends.

3. A cast side frame for car trucks having tension and compression members of inverted channel form, the corners of the tension member being located in planes laterally beyond the planes of the sides of the compression member.

4. A cast steel side frame for car trucks having tension and compression members of inverted channel formation, the width of the tension member being greater than the width of the compression member and at both ends being made abruptly greater than the members connected to its upper side.

In testimony whereof, I have signed this specification.

HARRY WALTER STERTZBACH.
